(57) **CLAIM**

The ornamental design for a reaction link for an aircraft, as shown and described.

DESCRIPTION

FIG. 1 is a perspective view of a reaction link for an aircraft according to our design;

FIG. 2 is a top plan view of the reaction link for the aircraft;

FIG. 3 is a bottom plan view of the reaction link for the aircraft;

FIG. 4 is a front elevational view of the reaction link for the aircraft;

FIG. 5 is a rear elevational view of the reaction link for the aircraft;

FIG. 6 is a left-side elevational view of the reaction link for the aircraft; and,

FIG. 7 is a right-side elevational view of the reaction link for the aircraft.

Any broken lines shown are included for the purpose of illustrating the environment of the design and form no part of the claimed design.

1 Claim, 5 Drawing Sheets
